COMBINED EDUCATIONAL FIGURE TOY AND VEHICLE OR SIMILAR ARTICLE

Louis M. Orren and Thomas M. Orren, Waco, Tex.

Application October 12, 1953, Serial No. 27,159

Term of patent 14 years

(Cl. D25—1)

To all whom it may concern:

Be it known that we, Louis M. Orren and Thomas M. Orren, both citizens of the United States, both residing at Waco, McLennan County, State of Texas, have invented a new, original, and ornamental Design for a Combined Educational Figure Toy and Vehicle or Similar Article, of which the following is a specification, reference being had to the accompanying drawing, forming a part hereof. The figure is a perspective view of a combined educational figure toy and vehicle or similar article showing our new design.

The side not shown has substantially the same appearance as the side shown in the single figure.

We claim:

The ornamental design for a combined educational figure toy and vehicle or similar article, as shown and described.
